UNITED STATES PATENT OFFICE.

WALTER FERRIS AND FREDERIC E. BAGER, OF SOUTH MILWAUKEE,
WISCONSIN, ASSIGNORS TO THE BUCYRUS COMPANY, OF SOUTH
MILWAUKEE, WISCONSIN, A CORPORATION OF WISCONSIN.

OPERATING MECHANISM FOR EXCAVATORS, DREDGES, AND THE LIKE.

No. 816,573.

Specification of Letters Patent.

Patented April 3, 1906.

Application filed June 9, 1905. Serial No. 264,388.

To all whom it may concern:

Be it known that we, WALTER FERRIS and FREDERIC E. BAGER, residing in the city of South Milwaukee, county of Milwaukee, State 5 of Wisconsin, citizens of the United States, have invented certain new and useful Improvements in Operating Mechanism for Excavators, Dredges, and the Like; and we do hereby declare the following to be a full, 10 clear, and exact description of the invention, such as will enable others skilled in the art to which it appertains to make and use the same.

The invention relates to excavators, dredges, and like machines which employ 15 winding-drums for operating the dippers or buckets, and has for its object to provide means in conjunction with the dipper or bucket operating drums for actuating the dipper or bucket supporting boom or the 20 dredge-holding spuds, or both, without reversing the engine, by means of which the drums are operated.

To this end the invention comprises two main drum-shafts driven in opposite directions from the engine or prime mover, an auxiliary drum-shaft which is operatively 25 connected to the swinging boom or to the spuds, and means for driving said auxiliary shaft from one or the other of the two main shafts, whereby the auxiliary shaft and the drums thereon may be driven in one direction or the other at will without changing the direction of movement of the respective main shafts and accordingly without reversing the 30 engine or motor.

Figure 1 is a plan view, partly in section, of 35 an operating system for an excavator or dredge embodying our invention. Fig. 2 is a plan view of the dredge, showing the connections between the operating-drums, the swinging-boom platform, and the spuds. Fig. 40 3 is a side elevation of the same. Fig. 4 is an end elevation showing the operation of the spuds, and Fig. 5 is a horizontal section of a 45 modified form of apparatus.

Referring to the drawings, and more particularly to Figs. 1 to 4, inclusive, A indicates the frame, upon which the engine or prime mover and the various operating-drums are 50 mounted.

a indicates the prime mover, which in this particular form of the invention is an ordi-

nary non-reversing steam-engine, to the crank-shaft b of which is applied a driving-gear c.

It is to be understood, of course, that any other suitable type of prime mover—as, for example, an electric motor—may be employed in lieu of the steam-engine.

Mounted upon suitable shafts f and g, supported on the frame or bed-plate A, are the two operating-drums h and o, which are connected to cables E and F for operating the dipper D in the usual well-known manner. Each of said drums is loosely mounted upon its respective shaft, and said shafts are geared to the engine crank-shaft by gears d and e, the former meshing with the pinion c on said crank-shaft and the latter gear e meshing directly with the gear d on crank-shaft f, so 65 that said shafts are rotated continuously, but in opposite directions, when the engine a is operating.

Drum h is provided with a band-clutch i, operated by a suitable link-and-lever mechanism i², i³, and i⁴, by means of which said drum may be coupled to or uncoupled from the shaft f. Drum o is provided with a similar clutch p, which is operated to couple or uncouple said drum to the shaft g by means 70 of similar link-and-lever mechanism p², p³, and r⁴. The operation of these two drums, as above indicated, serves to raise and lower and otherwise operate the dipper D in the manner well known in the art.

In machines of this general type it is necessary to swing the boom upon which the dipper is supported to the right and left to accommodate the apparatus to the varying conditions of work, and for this purpose it has been 75 customary to provide a separate drum operated from a reversible engine or motor, which drum is connected with the rotatory platform upon which the dipper-boom is mounted. When it was found necessary to employ spuds 80 or like anchoring means in apparatus of this character, separate spud-actuating drums were provided, which in turn were operated by drums driven from a reversible engine or motor.

In the present invention it is proposed to operate the dipper-boom and the spuds from the continuously-operating and preferably non-reversing engine a, which drives the dip-

per-operating drums. In the embodiment of the invention illustrated in Figs. 1 to 5 there is loosely mounted upon shaft f a gear j , which is provided with a band-clutch k , operated by suitable link-and-lever mechanism l , k' , and k^2 , which serves to connect and disconnect gear j with respect to the shaft f .

The shaft g is provided with a gear r , having a clutch s , operated by link-and-lever mechanism t , s' , and s^2 , by means of which said gear r may be connected to or disconnected from said shaft g at will. Between the gear j and the gear r is a transmission-pinion u , meshing with said gears. It is essential that the gear j and gear r be not simultaneously connected with their respective driving-shafts, and for this purpose the operating-levers l and t of the clutches k and s are connected by suitable links m' , m^2 with a common rock-lever m , so that when said lever m is in mid-position both clutches are uncoupled from the gear j and gear r , respectively, and when said lever m is moved to the right or left the gear j or the gear r only is coupled to its shaft. Meshing with the gear r is a gear v , loosely mounted upon a transverse shaft w , said gear v having elongated clutch-jaws v' . Upon the shaft w is keyed a sleeve v'' , located within the hub of gear v and provided with short clutch-jaws v''' . A sliding clutch b' , mounted loosely upon the shaft w , has long clutch-jaws b^3 , which are always in mesh with the long jaws v' on the gear v . Said clutch b' also has short jaws b^4 , adapted to mesh with clutch-jaws on the drum x when said clutch b' is moved to the right. The said drum x is loosely mounted upon shaft w and is adapted to operate a cable J , passing around the rotary table or platform I, upon which the dipper-boom C is mounted, the ends of said cable passing around drum x in opposite directions, so that as one bight of the cable is paid off the other is taken up by the drum. When the sliding clutch b' is moved to the left, its long jaws b^3 mesh with the jaws v''' of the sleeve v'' , which being keyed to the shaft w thereby connects said shaft to the gear v . Correspondingly, when the clutch b' is moved to the right the shaft w is disconnected from the gear v and drum x is coupled to said gear, whereas if the clutch b' is moved to mid-position, as indicated in the drawings, both the shaft w and the drum x are disconnected from the gear v .

Mounted loosely upon the shaft w are two spud-operating drums y and z , which serve to raise and lower the spuds S S by appropriate cables H I H' I', said drums being adapted to be alternately coupled to the shaft by a clutch a^3 , operated by link-and-lever mechanism a' , a^2 and to be uncoupled from said shaft when the clutch a^3 is moved to intermediate position. Pawls y' , z' , coöperating with suitable ratchet-rims on the drums y and z , serve

to lock said drums to hold the spuds in adjusted position.

In operating a dipper dredge of the character shown in the drawings the machine is moved ahead to a fresh cut and the spuds are run down by a heavy pull on the spud-ropes or cables, thereby "pinning up" and partially supporting the weight of the front end of the dredge upon the spud-ropes. The digging and swinging mechanism is put in operation—that is to say, the dipper is raised and lowered to scoop up and dump the material and is swung to and fro laterally by rotating the table I to the right and left. It will be seen that under these conditions the arrangement of the operating mechanism must be such that the shaft w will remain stationary during the swinging movement of the dipper-boom, because if said shaft were allowed to turn under the strain on the spud-operating drums y and z it would consume a great deal of power and rapidly wear out the bearings of these drums upon the shaft and also wear the shaft. It is therefore the purpose of this invention to provide means for driving the dipper-boom-operating drum without rotating the shaft w , upon which the latter is mounted, and for this purpose the gear v is adapted to be connected directly to the drum x by means of the clutch b' , having the long continuously-engaging jaws v' and b^3 between the said clutch and the gear v and the short jaws coupling said clutch to the drum x , when said clutch b' is moved to the right by the operating-lever b^2 . Under these conditions of operation the gear v is coupled directly to the drum x and no rotation is imparted to the shaft w .

When it is desired to swing the dipper-boom to the right, for instance, rock-lever m is swung to the right, thereby clutching gear j to the shaft f , and gear v is coupled to the drum x by the means just described. Drum x is thereby driven in the proper direction to wind up the right-hand hauling-rope and pay off the left-hand rope, thereby revolving the table or platform I to the desired point, after which the drum x is uncoupled from the gear v and the latter allowed to drive idly upon its shaft. It will be noted that the gear v is driven from the shaft f through the intermediate gear-train j , u , and r . When it is desired to swing the boom in the opposite direction, the lever m is swung to the left, thereby uncoupling gear j from its driving-shaft f and coupling gear r to shaft g , thereby imparting rotatory motion to the gear v in the opposite direction from that above noted, so that when the drum x is coupled to the gear v the table I is rotated to the left. By this means the swinging movement of the boom is accomplished without reversing the engine a and without in any way interfering with the normal operation of the dipper-operating drums

h and *o*. It will also be noted that when the lever *m* is moved to mid-position the train of gearing *j*, *u*, *r*, and *v* is not operated, as both of the gears *j* and *r* are uncoupled from their respective shafts.

In operating the spud-controlling drums *y* and *z* shaft *w* is clutched to the gear *v* by moving the clutch *b'* to the left until its long jaws *b*³ engage the short jaws *v'''* on sleeve *v''*, which is keyed to the shaft *w*, thereby coupling gear *v* to said shaft *w* by means of the clutch-jaws *v'*, *b*³, and *v'''*. The clutch *a*³ is then moved to couple drum *y* to the shaft *w*, and the left-hand spud *s* is pulled down by its cable and subsequently drum *z* is thrown into operation to pull down the right-hand spud, thereby pinning up the dredge, while the swinging drum *x* remains stationary. After each of the drums *y* and *z* have been operated to "pin up" the dredge said drums are locked in position by pawls *y'* and *z'*, respectively, which engage ratchet-rims on the drums, after which the clutch *a*³ is moved to mid-position, leaving the spud-ropes pulling against the pawls.

It will be apparent that the spuds may be withdrawn or lifted when it is desired to move the dredge to a new position by reversing the rotation of the gear *v*, so that the spud-operating drums *y* and *z* will also be reversed. After the dredge has been pinned up by the spuds and the clutch *a*³ has been moved to mid-position the clutch *b'* is withdrawn from engagement with the clutch-jaws *v'''* and engaged with the jaws on the drum *x*, thereby enabling the gear *v* to drive the drum *x* to effect the swinging of the dipper-boom without turning the shaft *w*, which is subjected to the heavy pull of the stationary spud-drums.

In the modified form of the invention illustrated in Fig. 5 the main operating-drums *h'* and *o'* are loosely mounted upon shafts *f'* and *g'*, which shafts are driven from a gear *c'* upon the engine-shaft, each of said shafts *f'* and *g'* having fast thereon meshing pinions *e'* and *d'*, the latter of which is driven directly from the gear *c'*. The respective drums *h'* and *o'* are adapted to be connected to their driving-shafts by clutches *i'* and *p'*. Loosely mounted upon the shafts *f'* and *g'* are gears *j'* and *r'*, which are adapted to be connected to their respective shafts by clutches *n* and *s*. Meshing with the gears *j'* and *r'* is an intermediate gear *u'*, mounted upon a shaft *w'*, upon which is mounted a drum *x'*, adapted to operate the cables running to the boom-platform of a dredge or excavator or the same general character as illustrated in Fig. 2. In this modification of the invention it will be noted that the gear *c'* is driven continuously in one direction from the prime mover and drives the shaft *g'* in one direction and the shaft *f'* in the other direction through the connected

gearing *d'* *e'*. By coupling gear *r'* to the shaft *g'* the drum *x'* will be driven in one direction and the gear *j'* will idle upon its shaft. Upon uncoupling gear *r'* from shaft *g'* and connecting gear *j'* to shaft *f'* by means of the clutch *k'* the drum *x'* will be driven in the opposite direction from the shaft *f'*, through the intermediate gearing *j'* and *u'*, while the gear *r'* idles. It will thus be seen that in this form of the mechanism also the auxiliary drum *x'* may be operated in either direction without reversing the direction of the engine and without in any way interfering with the normal operation of the main operating-drums *h'* and *o'*.

Having thus described our invention, we declare that what we claim, and desire to secure by Letters Patent, is—

1. Operating mechanism for excavators, dredges and the like, comprising a prime mover, two main drum-shafts driven in opposite directions thereby, an auxiliary drum-shaft, and means for driving said auxiliary shaft from one or the other of said main shafts, whereby the auxiliary shaft may be reversed without changing the direction of movement of said main shafts.

2. Operating mechanism for excavators, dredges and the like, comprising a prime mover, a main drum-shaft geared to said prime mover, a second main drum-shaft geared for opposite rotation to the main drum-shaft, an auxiliary drum-shaft, and gearing adapted to drive the auxiliary shaft from one or the other of said main drum-shafts, whereby the auxiliary shaft may be reversed without changing the direction of movement of said shafts.

3. Operating mechanism for excavators, dredges and the like, comprising a prime mover, two main shafts, drums mounted thereon, clutch mechanism adapted to connect the respective drums to their shafts, means for driving the main shafts in opposite directions from said prime mover, an auxiliary shaft, one or more drums on said auxiliary shaft, clutch mechanism for connecting the same to said shaft, loose gears on the respective main shafts, clutch mechanism for connecting the same to their respective shafts, and gears connecting the drive-shaft and the gears on the main shafts, whereby the auxiliary shaft may be reversed without changing the direction of motion of said main shafts.

4. Operating mechanism for excavators, dredges and the like, comprising a shaft, a gear loose upon said shaft, a plurality of drums loose upon said shaft, a clutch for coupling the gear to the shaft or to one of said drums, and a clutch for coupling the other drum or drums to the shaft.

5. Operating mechanism for excavators, dredges and the like, comprising a shaft, a

5 gear loose upon said shaft, a plurality of drums loose upon said shaft, a clutch for coupling the gear to the shaft or to one of said drums, a clutch for coupling the other drum or drums to the shaft, and means for driving said gear in either direction.

6. Operating mechanism for excavators, dredges and the like, comprising a shaft, a gear loose upon said shaft, a boom-operating drum loose upon said shaft, a clutch member fast to the shaft, a clutch member on the gear, a clutch member loose on the shaft coöoperating with said clutch members, and adapted to couple the gear to the shaft or to said 10 drum, spud-operating drums loose on said shaft and a clutch for coupling said spud-operating drums to the shaft.

7. Operating mechanism for excavators, dredges and the like, comprising a shaft, a gear loose upon said shaft, a boom-operating ²⁰ drum loose upon the shaft, clutch mechanism adapted to connect the gear to the shaft or to said drum, spud-operating drums loose on said shaft, clutch mechanism adapted to connect the latter drums to the shaft, and means for locking said spud-operating drums against rotation.

In testimony whereof we affix our signatures in presence of two witnesses.
